AUTOMATIC AIR-ARC GOUGER

Clifford M. Westfall, Peotone, Ill., assignor to Chicago Bridge & Iron Company, Chicago, Ill., a corporation of Illinois

Filed June 2, 1961, Ser. No. 114,470
8 Claims. (Cl. 314—5)

The present invention relates generally to apparatus for preparing plates which are to be welded in edge-to-edge relation, and more particularly to apparatus utilizing a carbon arc in conjunction with an air stream for gouging out a weldment-receiving channel along the junction between the edges of these plates.

In the construction of storage tanks, hoppers and the like, a plurality of plates are positioned in end-to-end relation and tacked or keyed in this position preparatory to welding along the junction between these plates. Heretofore, when these plates were placed in the preparatory position, it was necessary to space them a predetermined degree and bevel the edges beforehand to accommodate the weldment.

According to the present invention, edge spacing and beveling is no longer required and steel plates may be used as received from the rolling mill. More specifically, the present invention provides a carbon arc to burn a channel approximately halfway through said plates along the junction thereof, and a stream of air to blow the molten metal and slag out of the burned area leaving a clean channel to accommodate the weldment. This air-arc gouger is moved along the seams of the tank, hopper, or other workpiece by a conventional carriage such as that used to similarly carry seam-welding equipment, such carriages being well known to those skilled in the art (see Arnold U.S. Patent No. 2,713,106, issued June 12, 1955).

A feature of the present invention is apparatus for automatically feeding a continuous succession of carbon rods to the burning zone. More specifically, the subject invention provides means for continuously feeding a carbon rod to the burning zone, means for ejecting the burned-down stub of the carbon rod after the latter has been substantially consumed, and means for automatically replacing the burned-down stub with a new carbon rod.

Other features and advantages are inherent in the structure claimed and disclosed, as will be apparent to those skilled in the art from the following detailed description in conjunction with the accompanying drawings wherein:

FIGURE 1 is a plan view of an automatic air-arc gouger constructed in accordance with the present invention, and diagrammatically illustrating a pneumatic system therefor;

FIGURE 2 is a partially fragmented elevational view of the automatic air-arc gouger of FIGURE 1;

FIGURE 3 is a vertical sectional view taken substantially along line 3—3 of FIGURE 1, with portions of the pneumatic system removed for clarity of illustration;

FIGURE 4 is a sectional view taken substantially along line 4—4 of FIGURE 2, with portions of the pneumatic system removed; and

FIGURE 5 is a schematic view of the electrical circuitry for controlling the operation of the subject gouger.

Referring initially to FIGURES 3 and 4, there is shown an embodiment of the subject invention indicated generally by the numeral 10 and comprising a tubular barrel 12 having an upper slot 13 communicating with a magazine 14 holding a plurality of vertically stacked carbon rods 15. The lowermost of the carbon rods, 15a, drops through slot 13 into barrel 12 and is advanced forwardly 70 through the barrel (to the right in the figures) by an elongated pusher 16 mounted for back-and-forth move-

2

ment in a longitudinally slotted tube or cylinder 17 located in axial alignment with barrel 12 and to the rear thereof (to the left in the figures). Pusher 16 advances rod 15a forwardly so that the tip 20 of the rod extends outwardly through a pair of jaws 18, 19, which jaws engage the rod and electrically connect the latter to a power source for producing the gouging arc.

The rod tip 20 is steadily advanced toward the junction or seam between a pair of end-to-end plates (not shown) and, upon arcing, burns out a channel as the entire apparatus is moved along the seam by a conventional carriage (not shown). A stream of air is directed from an external air line 140 through a channel 139 in jaw 19 toward the area long the seam burned out by the tip 20 of the carbon rod, said stream of air cleaning out the molten metal and/or slag particles in the burned-out area to leave a clean channel for receiving a weldment.

When the carbon rod has burned down to a stub 15b (dash-dot lines), forward motion of pusher 16 is automatically stopped, jaws 18, 19 are automatically disengaged, stub 15b is automatically ejected, and pusher 16 is then retracted until the forward end thereof (to the right in the figures) clears the rearward end of slot 13 (to the left in the figures), thereby allowing a new carbon rod 15 to automatically drop into place in barrel 12, whereupon pusher 16 is again advanced to feed the new rod into a position to gouge out a channel.

Defining the entire structure now in greater detail, pusher 16 is shown to comprise a gear rack having a plurality of teeth 22 along one side thereof, said teeth being drivingly engaged by a pinion gear 23 mounted on a shaft 24 connected to the driven side of an electromagnetic clutch 25, the driving side of which is connected to a speed reducer 26 driven by an electric motor 27 mounted thereabove (FIGURES 1 and 2).

At the rear end of pusher 16 (to the left in the figures) there is attached a bracket 30 connected by a coupling 31 to a forwardly extending piston rod 32 terminating at a piston 33 enclosed within a pusher-actuating cylinder 34.

Located adjacent the forward end of cylinder 34 (to the right in the figures) is an irregularly shaped plate 40 upon which is mounted a jaw-actuating cylinder 41 from the forward end of which extends a piston rod 42 pivotally connected at 43 to a triangular-shaped plate or bell crank 44 pivoted at 45 on a flange 138 extending from a collar 230 mounted on barrel 12. Bell crank 44 is also pivotally connected at 46 to a link 47 attached to jaw 18.

Pusher 16 and piston rod 32 are linked to move forward and backward together. Jaw 18 opens and closes in response to movement of piston rod 42. Forward movement of piston rod 42 moves jaw 18 to a closed position for engaging a carbon rod between jaws 18 and 19. Jaw 19 is electrically connected to a power source by a cable inside air line 140; and when the carbon rod is engaged between the jaws, current flows through jaw 19 to the rod to produce the arc between the rod and the workpiece. Air flowing through line 140 cools the power cable. Rearward movement of piston rod 42 opens jaw 18 and disengages both jaws from the carbon rod.

The description of a typical cycle of operation may start with the elements in the positions shown in FIGURES 3 and 4. In these figures pusher 16 is at an intermediate station between extended and retracted positions thereof, and at this station a cam or projection 37 on bracket 30 has engaged and depressed a switch arm 101 (FIGURE 5) on a switch 195, thereby actuating a relay 102, in turn causing the energization of electromagnetic clutch 25 as well as the actuation of solenoid valves A, B and D (FIGURES 1, 2 and 5). As previously indicated, energization of clutch 25 turns gear 23

which engages the teeth 22 on pusher 16, thereby causing the latter to advance forwardly at a steady rate of speed, pushing rod 15a forwardly through barrel 12.

Referring now to FIGURES 1 and 2, illustrating an embodiment of a pneumatic system for operating portions of the subject apparatus, there is shown a main air line 103 extending through a filter 104, through an air pressure regulator 105 (said regulator having a branch connection to a pressure gauge 107), and to one side of a conventional oiler 106. The oiler introduces a trace of lubricant into the pneumatic system to facilitate movement of the valve parts. Extending from the other side of oiler 106 is a line 118 communicating with one side of a valve C and also with a second line 108. Line 108 communicates with one side of valve B and with an additional line 114 communicating with one side of valve A. The other side of valve A is connected by a line 109 to a connection 110 at the rearward end of jaw-actuating cylinder 41. Energization of relay 102 opens valve A, thereby causing air to flow through valve A, line 109, and connection 110 into the rear end of cylinder 41, thereby advancing its piston and piston rod 42 in a forward direction to close jaw 18 and engage jaws 18, 19 around the carbon rod.

Energization of relay 102 also opens valve D, which is connected by lines 111 and 117 to a connection 112 at the forward end of cylinder 41. As the piston within cylinder 41 advances forwardly, air escapes from the forward end of the cylinder through connection 112, lines 117 and 111, and is exhausted through valve D.

As the forwardly moving pusher 16 reaches its extended position at the end of the forward stroke, a cam or projection 38 on bracket 30 engages and depresses a second switch arm 131 (FIGURE 5) on a switch 196, thereby energizing a second relay 132 in turn actuating and opening solenoid valves C and F, while at the same time deenergizing relay 102, said deenergization of relay 102 causing valves A and D to close and valve B to open.

The opening of valve C causes air to flow therethrough, and through a line 119 to a connection 120 at the forward end of barrel 12. Air entering barrel 12 through connection 120 ejects the stub 15b left therein at the end of the forward stroke of pusher 16.

At the same time as cam 38 on bracket 30 engages and depresses switch arm 131, a projection 39 on bracket 30 depresses a pin 124 on a poppet valve 125 connected by a line 126 to a connection 127 on a conventionally constructed spool-containing valve E. Opening of poppet valve 125 bleeds valve E and causes a repositioning of the spool within valve E so that air entering the latter through a line 115 from the now-open valve B will be directed through a connection 116 to line 117 and then to connections 112, 113 at the forward ends of cylinders 41, 34 respectively. This causes movement of respective piston rods 42, 32 in a rearward direction (to the left in the figures).

Movement of piston rod 32 in a rearward direction retracts pusher 16. Movement of piston rod 42 in a rearward direction opens jaw 18, thereby facilitating removal of stub 15b by substantially simultaneous injection of air through connection 120 at the forward end of barrel 12. During the rearward movement of piston 33 in cylinder 34 air is exhausted from the rear of cylinder 34 through connection 122, lines 123 and 121, and open valve F. Air is exhausted through the rearward end of cylinder 41 through connection 110, line 109, and an opening in valve A.

At the conclusion of the rearward stroke, cam 38 on bracket 30 engages and depresses a switch arm 141 (FIGURE 5) on a switch 197 to open the circuit to relay 132, thereby deenergizing the latter and deactuating solenoid valves C and F, thus causing the latter two valves to close. Simultaneously, the rear surface 127 of bracket 30 engages a depressable pin 128 on a poppet valve 129 connected by a line 130 to valve E. Opening of valve

129 bleeds valve E to cause a repositioning of the spool within valve E to a position whereby air entering valve E through line 115 (from the still-open valve B) is directed through connection 137 and line 123 to the connection 122 at the rearward end of cylinder 34. This causes forward movement of piston 33 and piston rod 32, in turn advancing pusher 16 forward to its intermediate station in which the stud 37 on bracket 30 once again engages and depresses the switch arm 101.

As previously described, depression of switch arm 101 causes energization of relay 102 and actuation of valve B so as to close the latter. Since valve B is closed, air from the main air line can no longer enter valve E or line 123 or the rear end of cylinder 34. Thus further advancement of pusher 16 by pneumatic means is stopped. However, energization of relay 102 also energizes electromagnetic clutch 25 so that pusher rod 16 is now advanced by the engagement of rotating gear 23 with the teeth 22 on the rack-like pusher 16. The advancing pusher 16 engages and pushes forward a carbon rod which dropped through the slot 13 in the top of barrel 12 to fill up the space vacated by the pusher as it returned to its retracted position.

134 and 136 represent manually actuatable poppet valves connected by lines 133, 135, respectively, to valves 125, 129, respectively, and provide emergency means for bleeding valve E.

Referring to FIGURE 5, an electrical circuit for the subject apparatus will now be described in greater detail. The subject apparatus receives its power from a circuit including main power lines 161, 162 and a main power switch 163. Motor 27 is connected in parallel to the main power lines by a circuit including lines 164, 165, switch 166 and rectifier 167.

Describing, now, the circuit for energizing relay 102 the relay coil 189 has one terminal 168 normally connected to main power line 162 by line 200, terminal 156 on switch 196, switch arm 131, and terminal 155 on switch 196. The other terminal 169 of relay coil 189 is connected by line 201 to a terminal 153 on switch 195. Consequently, when pusher 16 reaches its intermediate station, and the arm 101 of switch 195 is moved by cam 37 from terminal 154 on switch 195 to terminal 153, the second terminal 169 of relay coil 189 becomes connected to main power line 161 by a circuit comprising line 201, terminal 153, switch arm 101, terminal 152 on switch 195, line 202, terminal 171 on relay 102, line 203, terminal 179 on relay 132, internal line 193 in relay 132, movable contact element 187 in relay 132, terminal 181 in relay 132, line 204, and terminal 160 on switch 197. With both terminals of its coil 189 thus connected to respective power lines, relay 102 becomes energized.

Relay 102 remains energized even after switch arm 101 has returned from its closed position, in contact with terminal 153 on switch 195, to its normal open position in contact with terminal 154 on switch 195. More specifically, the terminal 168 on relay coil 189 is still connected to main power line 162 by the circuit previously described. The other terminal 169 on coil 189 is connected to main power line 161 by line 205, terminal 175 on relay 102, movable contact element 185 in relay 102 (said element moving into contact with terminal 175 upon energization of relay 102), internal line 191 in relay 102, terminal 171 on relay 102, and line 203 which is connected to the main power line 161 by a circuit already described.

Relay 102 remains energized until arm 131 on switch 196 is moved from its normal position in contact with terminal 156 on switch 196, said movement occurring when pusher 16 reaches its extended position and arm 131 is engaged by cam 38. This movement of arm 131 breaks the circuit between terminal 156 (connected to coil terminal 168 on relay 102) and main power line 162, thereby deenergizing the coil on relay 102.

The actuation of solenoid valves A, D and B, and

the energization of clutch 25, upon energization of relay 102, is as follows. When relay 102 is energized, the movable contact elements 184, 185 move from terminals 172, 173 respectively to terminals 174, 175 respectively. Relay contact 184 is connected to main power line 161 by relay internal line 190, terminal 170 on relay 102, line 214, terminal 181 on relay 132, line 204, and terminal 160 on switch 197. Movement of contact element 184 into contact with element 174 connects one side of each of the solenoid valves A, D and B, and one side of clutch rectifier 188 to main power line 161 by virtue of the connection of terminal 174 with lines 208, 209, 206, 207 respectively.

Each of the previously described solenoid valves and the clutch rectifier has another side connected to main power line 162 by the following circuits. Valves B, A and D are connected to terminal 155 on switch 196 by lines 210, 211, and 212 respectively. Rectifier 188 is connected to terminal 155 by line 213. As previously described, terminal 155 is directly connected to line 162. Accordingly, when relay 102 is actuated to move the contact element 184 into contact with element 174, solenoid valves A and D are opened, solenoid valve B is closed, and current flows through rectifier 188 to energize electromagnetic clutch 25. As previously indicated, clutch 25 remains energized and solenoid valves A, D and B remain actuated until arm 131 on switch 196 is moved out of contact with terminal 156 on switch 196, by the engagement of cam 38 with arm 131 when pusher 16 reaches its extended position.

The energization of relay 132 is as follows. The relay coil 192 has one terminal 177 normally connected to main power line 161 by line 215, terminal 158 on switch 197, switch arm 141, and terminal 160 on switch 197. The other relay coil terminal 176 is connected to terminal 157 on switch 196. As previously indicated, when pusher 16 reaches its extended position, cam 38 engages switch arm 131. This moves arm 131 into contact with terminal 157. As a result, terminal 176 on relay coil 192 becomes connected to main power line 162 by a circuit including line 216, terminal 157, switch arm 131, and terminal 155 which is directly connected to main power line 162; and relay 132 becomes energized.

Energization of relay 132 actuates solenoid valves C and F in the manner described below. Energization of relay 132 causes movement of this relay's movable contact elements 186, 187 from relay terminals 180, 181 respectively to relay terminals 182, 183 respectively. Terminal 182 is connected by lines 217, 218 to a respective side of solenoid valves C and F respectively. Each of these solenoid valves has another side connected by lines 219, 220 respectively to terminal 177 on relay 132 which in turn is connected to power line 161 by line 215, terminal 158 on switch 197, switch arm 141, and terminal 160 on switch 197. Accordingly, movement of contact element 186 into contact with terminal 182 connects solenoid valves C and F with both power lines, thereby actuating and opening these valves.

Relay 132 remains energized even after the switch arm 131 has moved back from its engagement with terminal 157 on switch 196 to its normal position in contact with terminal 156 on switch 196, said return movement occurring after switch arm 131 has been disengaged from cam 38 on bracket 30. More specifically, relay coil terminal 177 is still connected to main power line 161 by the circuit including line 215, terminal 158 on switch 197, switch arm 141, and terminal 160. The other relay coil terminal 176 is connected to main power line 162 by a circuit including line 221, terminal 182 on relay 132, movable contact element 186 on relay 132 (moved into contact with terminal 182 upon energization of relay 132), internal line 194 in relay 132, terminal 178 on relay 132, line 222, and terminal 155 on switch 196.

Relay 132 is deenergized when arm 141 on switch 197 is moved from its normal position in contact with ter-

75 minal 158 on switch 197 toward terminal 159 by virtue of the engagement of arm 141 by cam 37 on bracket 32, said engagement occurring when the pusher 16 is returned to its retracted position. Movement of switch arm 141 out of contact with terminal 158 breaks the circuit between coil terminal 177 on relay 132 and main power line 161. Accordingly, the relay is deenergized and solenoid valves C and F are returned to their deactuated condition.

10 There has thus been described an apparatus for gouging out a channel at the junction between a pair of plates disposed in end-to-end relation, said apparatus utilizing a carbon rod to produce an arc for burning out the channel and a stream of air for cleaning out the molten metal or slag particles from the burned-out area. In addition, the above-described apparatus includes, as a primary feature, means for feeding a continuous succession of carbon rods to the burning zone. More specifically, the apparatus comprises means for continuously advancing a carbon rod toward the workpiece as the rod burns down, means for ejecting the burned-down stub of the carbon rod after the latter has been substantially consumed, and means for automatically replacing the burned-down stub with a new carbon rod.

15 The foregoing detailed description has been given for 20 clearness of understanding only, and no unnecessary limitations should be understood therefrom, as modifications will be obvious to those skilled in the art.

25 I claim:

30 1. In an apparatus for gouging a channel on a metal workpiece:

35 barrel means for receiving a carbon rod; pusher means at the rearward end of said barrel means; means mounting said pusher means for reciprocal movement in forward and rearward directions from a retracted position through an intermediate position to an extended position and then back to said retracted position; means on said pusher means for engaging the rearward end of said carbon rod when the pusher means moves forwardly from its intermediate position and for advancing the rod in a forward direction, towards an area to be arc gouged on the workpiece, when the pusher is moving forward from its intermediate position toward its extended position;

40 jaw means at the forward end of said barrel and actuatable to engage said advancing carbon rod; mechanical driving means actuatable in response to attainment by said pusher means of said intermediate position for advancing the pusher means from its intermediate position to its extended position at a steady deliberate rate;

45 first fluid driving means actuatable in response to attainment by the pusher means of its extended position for rapidly retracing the pusher means from its extended position to its retracted position; and second fluid driving means actuatable in response to attainment by the pusher means of its retracted position for rapidly advancing the pusher means from its retracted position to its intermediate position.

50 2. An apparatus as recited in claim 1 and comprising: means responsive to advancement of the pusher means to its intermediate position for actuating said jaw means to engage said rod; and means actuatable in response to attainment by the pusher means of its extended position for disengaging said jaw means from the rod.

55 3. The apparatus of claim 1 wherein both said jaw actuating means and said jaw disengaging means are fluid driven.

60 4. An apparatus as recited in claim 1 and comprising: means actuatable in response to attainment by the pusher means of its extended position for ejecting the portion of the carbon rod not consumed during the arc gouging operation.

65 5. An apparatus as recited in claim 4 wherein said rod

ejecting means comprises means for directing a stream of fluid against the rearward end of the carbon rod remaining in said barrel.

6. An apparatus as recited in claim 1 and comprising: means responsive to advancement of the pusher means through its intermediate position for actuating said jaw means to engage said rod; means actuatable in response to attainment by the pusher means of its extended position for disengaging said jaw means to engage said rod; and means actuatable in response to attainment by the pusher means of its extended position for ejecting the unconsumed portion of the carbon rod.
7. An apparatus as recited in claim 6 wherein: both said jaw actuating means and said jaw disengaging means are fluid driven; and said rod ejecting means comprises means for direct-

ing a stream of fluid against the rearward end of the carbon rod remaining in said barrel.

8. An apparatus as recited in claim 1 and comprising means responsive to the retraction of the pusher means behind said intermediate position thereof for introducing a new carbon rod into said barrel means.
